SHOE SEWING MACHINE

Erastus E. Winkley, Lynn, Mass., assignor to
 United Shoe Machinery Corporation, Borough
 of Flemington, N. J., a corporation of New
 Jersey

Application December 18, 1939, Serial No. 309,791.

10 Claims. (Cl. 112—221)

The present invention relates to shoe sewing machines, and more particularly to inseam sewing machines for use in sewing together the upper and sole of a turn shoe, or the welt, upper, and insole of a welt shoe.

An example of this class of machine is the well-known Goodyear welt and turn shoe sewing machine which is disclosed in the patent to Eppler, No. 1,108,560, dated August 25, 1914. In this machine, as in other machines of the class employing a curved hook needle operating from the outside of the shoe, difficulty has been experienced in arranging the needle and the work so that the needle may pierce the between-substance at the base of the lip and emerge free and clear of the sole back of the channel, especially where a so-called "economy" or canvas backed insole is employed, without requiring objectionable tipping of the shoe or bringing the needle into improper position to be looped.

Accordingly, it is an object of the present invention to provide, in this class of machine, a needle which will pierce the between-substance and emerge at the base of the lip clear of the sole, and which will thereafter advance into a position which will enable the looper readily to lay the thread into the barb of the needle.

With this object in view, a feature of the invention involves the provision in a machine of the class referred to of a hook needle having a plurality of curvatures and a needle carrier adapted to be oscillated about centers concentric with these curvatures. More specifically, it is contemplated that the curvature of the needle in the vicinity of the barb be of lesser radius than the curvature of the shank, the needle carrier being oscillated about a center concentric with the shank portion of the needle to advance the barb into thread-receiving position forwardly of the machine. The arrangement thus provides the advantages of a short radius needle, with its ability to place the seam at the base of the lip and emerge free of the work inwardly thereof, but without rendering difficult the proper looping of the needle after it has passed through the work.

In the drawings illustrating the invention, Figure 1 is a view in right side elevation, partly in section, of an inseam shoe sewing machine embodying the present invention, the machine being of the same general construction and arrangement as described in the patent to Eppler above 55

referred to; Figure 2 is a detail view in side elevation adjacent the sewing point of the machine, showing the needle, needle carrier, and certain actuating connections of the invention, the needle being shown in fully retracted position; Figure 3 is a view similar to Figure 2 but after the needle has emerged from the inside shoulder of the lip, the needle carrier up to this point having been oscillated about a center concentric with the portion of the needle having the shorter radius of curvature; Figure 4 is a detail view in front elevation of the parts shown in Figure 3; and Figure 5 is a view in side elevation similar to Figures 2 and 3 but with the needle at the limit of its work penetrating stroke and in position to be looped, the needle carrier having been oscillated from the position shown in Figure 3 about a center concentric with the longer radius shank portion of the needle.

20 Referring to Figure 1 of the drawings, the back rest of the machine is indicated at 6, the needle at 8, the looper at 10, and the thread finger at 12, the parts with the exception of the needle being actuated from the sewing shaft 14 in the manner of the Eppler patent above referred to.

25 The needle 8 differs from the usual curved hook needle in that the portion adjacent and including the barb 16 is curved in an arc of relatively small radius as compared with the radius of curvature 30 of the remainder or shank portion 18 of the needle.

35 The needle is clamped in a needle carrier 20 which, instead of being supported in the usual manner for oscillation about a single center, is 40 arranged to permit oscillation about more than one center, so that the needle may be rocked about centers concentric with its various curvatures as the different portions of the needle pass through the work. To this end, the needle carrier 20 is mounted for pivotal movement about a stud 22 secured in an arm 24 which is carried by a shaft 26 journaled in the machine frame 28 in approximately the location of the conventional needle carrier stud.

45 The bearing for the pivot stud 22 in the needle carrier is concentrically disposed with respect to that portion of the needle having the shorter radius of curvature so that when the needle carrier is rotated about the stud, the portion of the needle in the vicinity of the point and barb may readily pass through the work. The location of the stud 22 in the arm 24, on the other hand, is such that its radial distance from the center of supporting shaft 26 is equal to the difference be-

tween the longer and the shorter radii of curvature of the needle portions.

The stud 22 is connected by means of a link 30 with one arm of a bell crank lever 32 pivotally supported on a cross shaft 34 at the rear of the machine. The other arm of the bell crank is provided with a follower 36 operating in a cam groove 38 in one face of a cam disc 40.

In addition to being pivotally mounted on stud 22, the needle carrier 20 is provided with a second pivotal center comprising a stud 42 fixed in the carrier at a point concentric with the shank or longer radius portion of the needle. This stud is provided with separate actuating connections comprising link 44 and cam actuated lever 46 having a follower 48 operating in cam groove 50 in the other face of the cam disc 40.

The cam grooves 38 and 50 are laid out to cause the needle carrier to be rocked, during the advancing and retracting strokes of the needle, about centers appropriate to the curvatures of the various portions of the needle as each portion passes through the work. Starting with the parts in the position shown in Figure 2 of the drawings, the needle is shown in retracted position preparatory to piercing the upstanding lip 52 in securing the welt 54 and upper 56 to an insole 58 provided with a canvas covering or backing 60.

During the preliminary portion of the work piercing stroke of the needle, the needle carrier is rocked about a center concentric with the short radius portion of the needle. This is effected by rocking the needle carrier 20 about stud 22 as a center, the arm 24 in which the stud is mounted being held in a downwardly directed position by the constant radius portion 62 of cam groove 38. At the same time, the cam lever 46 is rocked in clockwise direction by the portion 64 of cam groove 50 to cause the link 44 to rock the needle carrier about the stud 22 through an arc of approximately 90°, to substantially the position shown in Figure 3, which shows the short-radius portion of the needle emerging from the work at the base of the lip 52. By reason of the short radius of curvature and oscillation of the needle, the needle is enabled to strike into the welt and upper at a relatively steep angle and pierce the lip at the very base thereof, and yet emerge on the inside of the lip just clear of the surface of the insole back of the lip thus avoiding catching or otherwise disturbing the canvas backing 60.

For the remainder of its advancing stroke, the needle is rocked about a center concentric with its longer radius shank portion, in order that the barb 16 may advance into a position well forwardly of the position it would otherwise reach if the entire needle was of a short radius of curvature and rocked about a single center. As shown in Figures 3 and 4, which illustrate the needle and needle carrier at the limit of their advance about the "short-radius" center, namely stud 22, the needle carrier has reached a position in which the stud 42, representing the center of the longer-radius portion of the needle, is in substantial alignment with the shaft 26. The stud 42 is now held from displacement while the needle carrier 20 and supporting arm 24 are rocked as a unit about said stud and shaft as a center to the position illustrated in Figures 1 and 5. The stud 42 is held in alignment with the shaft 26 by the constant radius portion 66 of the cam groove 50, while the bell crank 32 is rocked in clockwise direction by portion 68 of

cam groove 38. The needle is maintained in its fully advanced position for such time as is required for the looper 10 properly to lay the thread in the barb of the needle, the dwell being provided by constant radius portions 72 and 66 of cam grooves 38 and 50 respectively.

Upon completion of the looping operation, the needle is retracted in a manner just the reverse of its piercing stroke. While the shank portion 18 is being withdrawn, the needle is rocked about the "long radius" center by cam lever 32 and link 30. After the needle has been retracted as far as the position shown in Figure 3, the stud 22 is held from further bodily displacement and the needle carrier rocked about said stud as the "short radius" center while the portion of the needle having the greater curvature is withdrawn from the work and the needle moved to fully retracted position as in Figure 2.

While the invention has been illustrated and described as embodied in a shoe sewing machine of particular construction and arrangement, the invention is not so limited, but may be embodied in machines of other forms and arrangements within the scope of the appended claims.

Having thus described the invention, what is claimed is:

1. An inseam shoe sewing machine having, in combination, stitch forming devices including a hook needle having a plurality of curvatures of different radii, said curvatures being concentric with a plurality of centers disposed at spaced points, a needle carrier, and means for oscillating the needle carrier successively about said centers concentric with the respective curvatures of the needle.

2. An inseam shoe sewing machine having, in combination, stitch forming devices including a hook needle having a plurality of curvatures, a needle carrier, a plurality of pivotal supports for said carrier concentric with the curvatures of the needle, and means for rocking the needle carrier about successive pivotal supports.

3. An inseam shoe sewing machine having, in combination, stitch forming devices including a hook needle having a plurality of curvatures of different radii, said curvatures being concentric with a plurality of centers disposed at spaced points, a needle carrier, and means connected to the needle carrier at a plurality of pivotal points for rocking the needle carrier successively about said centers concentric with the respective curvatures of the needle.

4. An inseam shoe sewing machine having, in combination, stitch forming devices including a hook needle having a plurality of curvatures of different radii, said curvatures being concentric with a plurality of centers disposed at spaced points, a needle carrier, and means for actuating the needle carrier to cause the needle to enter and withdraw from the work comprising a plurality of members pivotally connected to the needle carrier and means for actuating said members to rock the needle carrier successively about said centers concentric with the respective curvatures of the portions of the needle as they pass through the work.

5. An inseam shoe sewing machine having, in combination, stitch forming devices including a hook needle having a plurality of curvatures of different radii, said curvatures being concentric with a plurality of centers disposed at spaced points, a needle carrier, and means for actuating the needle carrier to cause the needle to enter and withdraw from the work comprising a

plurality of links pivotally connected to the needle carrier and a plurality of cam-actuated levers for actuating the links in timed relation to the passage of the needle through the work whereby the needle may be rocked successively about said centers concentric with the respective curvatures of the portions of the needle as they pass through the work.

6. An inseam shoe sewing machine having, in combination, stitch forming devices including a curved hook needle, the portion of the needle adjacent the point having a lesser radius of curvature than the shank portion of the needle, and means for rocking the needle about centers concentric first with one curvature of the needle and then another.

7. An inseam shoe sewing machine having, in combination, stitch forming devices including a curved hook needle, the portion of the needle adjacent the point having a lesser radius of curvature than the shank portion of the needle, a needle carrier actuated to cause the needle to enter and to withdraw from the work, and means for supporting the needle carrier for oscillation about a center concentric with the curvature of the lesser radius portion of the needle while the portion adjacent the point is passing through the work and about a center concentric with the curvature of the shank of the needle while the latter portion is passing through the work.

8. An inseam shoe sewing machine having, in combination, stitch forming devices including a curved hook needle, a pivoted support, a needle carrier pivotally mounted on the support, and means for rocking the needle carrier about the pivot on the support and thereafter rocking the needle carrier and the support about the pivot of the support.

9. An inseam shoe sewing machine having, in

combination, stitch forming devices including a curved hook needle, the portion of the needle adjacent the point having a lesser radius of curvature than the shank portion of the needle, a needle carrier, a pivoted support, a pivotal connection between the support and needle carrier concentric with the portion of the needle having the lesser radius of curvature and spaced from the pivot of the support a radial distance equal to the difference between the greater and the lesser radii of curvature of the needle portions, and means for rocking the needle carrier about its pivotal connection with the support relative to said support while the portion of the needle adjacent the point is passed through the work and for rocking the needle carrier and support as a unit about the pivot of the support while the shank of the needle is in the work.

10. An inseam shoe sewing machine having, in combination, stitch forming devices including a curved hook needle having a radius of curvature adjacent its point less than the radius of curvature of the shank portion, a needle carrier, a pivoted support, a pivotal connection between the support and carrier concentric with the portion of the needle having the lesser radius of curvature, a link pivotally connected to said pivotal connection, a second link pivotally connected to the needle carrier at a point concentric with the shank portion of the needle, and means for successively actuating the links to cause the first link to hold the support while the second link rotates the needle carrier about the pivotal connection and thereafter to cause the second link to hold the needle carrier with the link pivot concentric with the pivot of the support while the first link rotates the needle carrier and the support as a unit about the pivot of the support.
